UNITED STATES PATENT OFFICE.

WENDELL P. BOSWORTH, OF BROCKTON, MASSACHUSETTS, ASSIGNOR TO BROCKTON HEEL COMPANY, OF BROCKTON, MASSACHUSETTS, A CORPORATION OF MASSACHUSETTS.

MACHINE FOR MAKING HEEL-LOGS.

1,076,742.

Specification of Letters Patent. Patented Oct. 28, 1913.

Application filed February 21, 1913. Serial No. 749,850.

To all whom it may concern:

Be it known that I, WENDELL P. BOSWORTH, a citizen of the United States, and a resident of Brockton, in the county of 5 Plymouth and State of Massachusetts, have invented certain new and useful Improvements in Machines for Making Heel-Logs, of which the following is a specification.

This invention relates to a machine of 10 the type shown by Letters Patent of the United States No. 936,858, dated October 12, 1909, comprising a rigid vertical heel-shaped mold which is open at both ends, means for pressing cement or paste-coated 15 heel lifts into and through said mold, the lifts being laterally contracted and pressed together while passing through the mold and thus forming a vertical assemblage of lifts known as a heel log, and an elongated 20 vertical guide of indeterminate length below the mold and communicating therewith, the guide receiving the heel log as it emerges from the mold, and directing the log in its downward course, the cement or paste being 25 gradually dried while the log is passing through the guide so that the lower end of the log which emerges from the guide is practically rigid and is adapted to be converted into heel logs of any desired thick- 30 ness, preferably by cutting off the part of the log which protrudes from the lower end of the guide and sub-dividing the cut-off portion into heel bodies or blanks by a suitable cutting or slicing machine. In the machine of said prior patent, the guide is 35 composed of rigidly connected longitudinal bars which are spaced apart to expose portions of the log and permit the same to dry quickly, the lower end of the log being sup- 40 ported by a sliding platform or rest which is movable within the guide and is yield- 45 ingly supported by weighted cords, the object of said rest being to prevent the lower portion of the log from being broken off from the upper portion by its own weight. When a log exceeding the combined length 50 of the mold and guide has been formed, the rest projects with the lower end of the log below the guide and has to be temporarily displaced while the protruding portion of the log is being detached, the rest being subsequently returned to the position to support the lower end of the log.

The present invention has for its object

to dispense with the said sliding rest or 55 platform and to enable the guide bars to yieldingly support the log and prevent the breakage of the log by its own weight, the lower end of the guide being continuously 60 unobstructed to permit the lower end of the log to emerge therefrom and be cut off without the inconvenience involved in displacing the rest of the said prior patent and returning it to place.

The invention consists in the improve- 65 ments which I will now proceed to describe and claim.

Of the accompanying drawings forming a part of this specification,—Figure 1 represents a side elevation of a portion of a heel- 70 log-building machine embodying my invention. Fig. 2 represents a longitudinal section on the line 2—2 of Fig. 1. Fig. 3 represents a transverse section on the line 3—3 of Fig. 1. Fig. 4 represents a transverse sec- 75 tion on the line 4—4 of Fig. 1.

In the drawings,—*a* represents a rigid vertical mold which is open at both ends and is adapted to receive and laterally contract an assemblage of heel lifts *b* which 80 have been coated with paste and inserted in the upper end of the mold, each lift being either composed of a single piece or, as shown by Figs. 3 and 4, of a plurality of sections forming a pieced lift. The mold is rigidly 85 secured to a casing or holder *c* forming a part of the frame of the machine, said holder being for the purposes of this invention considered as a part of the mold.

d represents a vertical heel-shaped plun- 90 ger which is adapted to be vertically re- ciprocated and to enter the upper end of the mold and press downwardly therein a lift or assemblage of lifts *b*, the lifts being 95 placed in the upper end of the mold by an attendant while the plunger is raised. The plunger, which may be operated by mechanism shown in the above-mentioned patent or any other suitable mechanism, forces the lifts downwardly step-by-step through the 100 mold, the rigid walls of the mold passage or opening sufficiently resisting the down- 105 ward movement of the freshly coated lifts to impart the desired form to their margins and cause close contact between their opposed surfaces, so that an assemblage of lifts extending from the upper portion to the lower end of the mold

constitutes a heel log which is caused to emerge from the lower end of the mold by the continued operation of the machine.

Owing to the degree of frictional resistance offered by the rigid walls of the mold to the downward movement of the heel lifts therein, it is desirable to limit the length of the mold, making it much shorter than the distance between the upper end of the mold 5 and the lower part of the heel log which is sufficiently dried and hardened. In practice, the length of the rigid mold is necessarily limited to a few inches to obviate the necessity of undue resistance to the downward movement of the log by the plunger *d*.

In carrying out my invention, I provide below the mold *a* a series of preferably four elongated vertical guide bars 12 which are loosely supported and are movable laterally 10 to a limited extent independently of each other, and means for pressing said guide bars yieldingly against the surface of the portion of the heel log which projects below the mold. The guide bars 12 are formed to 15 bear on portions of the perimeter of the heel log, as shown by Figs. 3 and 4, and each bar is preferably made of metal of angular form in cross section, two of the bars being preferably provided with cheek pieces 13 which 20 may be of wood and have their inner surfaces curved to conform to portions of the curved surface of the heel log. The guide bars are preferably suspended from the lower portion of the mold by means of suspension rods 14 pivoted at their upper ends 25 to the mold or to the casing *c* thereof, and at their lower ends to the guide bars at points below the mold, as shown by Figs. 1 and 2, which show studs 15 attached to the mold 30 casing *c* and engaged with eyes at the upper ends of the rods 14, and studs 16 attached to the guide bars and engaged with eyes at the lower ends of the rods. The guide bars 35 are thus adapted to move laterally to a limited extent independently of each other and at the same time are securely supported against downward displacement. The lower end of the mold and the upper ends of the guide bars are provided with interlocking 40 members adapted to prevent lateral movement of the upper ends of the bars, these members including an extension 17 of the mold fitting within extensions 18 of the guide bars, so that the proper passage of the 45 log from the mold into the space between the guide bars is insured.

For pressing the guide bars against the heel log, I prefer to employ contractile springs 19 attached at their ends to studs 50 on adjacent guide bars, said springs being preferably arranged in sets each including four springs as shown by Fig. 3. The sets of springs are suitably spaced apart, the distance between each set of springs and the 55 next and the number of sets employed de-

pending upon the cross-sectional area and weight of the heel log, the object being to cause a pressure of the guide bars against the heel log sufficient to prevent the breaking of the lower portion of the heel log by 70 its own weight, without offering undue resistance to the downward movement of the heel log by the plunger *d*.

I prefer to provide the guide bars with sockets 22 and steady pins 23 slidably engaged with said sockets, each bar being provided with a steady pin 23 engaging a socket 22 on the next bar, and the steady pins and sockets forming a set or series surrounding the guide bars, as shown by Fig. 4. The sets 75 of sockets and steady pins preferably alternate with the sets of springs 19, as shown by Fig. 1. These devices tend to keep the bars 80 in parallelism with each other.

The length of the guide bars is preferably 85 from thirty to sixty feet so they are adapted to control a log of corresponding length, this length being such that there is ample time for the paste to dry and harden between the lower end of the mold and the lower end 90 of the guide formed by the guide bars. Said lower end is continuously open and unobstructed so that the protruding dry and hardened end of the heel log may be conveniently removed as required. 95

I claim:

1. A heel-log-building machine comprising a rigid vertical mold open at both ends, means for pressing lifts into and through said mold to form a heel log, elongated vertical guide bars supported below said mold and adapted to guide a heel log emerging therefrom, and means for yieldingly pressing the guide bars against the heel log, whereby breakage of the log by its own weight is prevented, the lower end of the guide formed by said bars being continuously unobstructed to permit the lower end 105 of the log to emerge therefrom.

2. A heel-log-building machine comprising a rigid vertical mold open at both ends, means for pressing lifts into and through said mold to form a heel log, elongated vertical guide bars supported below said mold and adapted to guide a heel log emerging 110 therefrom, and transverse contractile springs connecting the guide bars and adapted to yieldingly press their inner sides against the heel log. 115

3. A heel-log-building machine comprising a rigid vertical mold open at both ends, means for pressing lifts into and through said mold to form a heel log, elongated vertical guide bars supported below said mold and adapted to guide a heel log emerging 120 therefrom, and transverse contractile springs connecting the guide bars and adapted to yieldingly press their inner sides against the heel log, the bars being provided with steady pins and sockets alternating with said 125 130

springs, the steady pins of each bar being in sliding engagement with sockets on an adjacent bar.

4. A heel-building machine comprising a rigid vertical mold open at both ends, means for pressing lifts into and through said mold to form a heel log, elongated vertical guide rods loosely supported below the mold and capable of independent lateral movement, and means for yieldingly pressing the guide bars against the heel log.

5. A heel-building machine comprising a rigid vertical mold open at both ends, means for pressing lifts into and through said mold to form a heel log, elongated vertical guide rods loosely supported below the mold and capable of independent lateral movement, and means for yieldingly pressing the guide bars against the heel log, the upper ends of the bars and the lower end of the mold being

provided with interlocking members adapted to prevent lateral movement of the upper ends of the bars.

6. A heel-building machine comprising a rigid vertical mold open at both ends, means for pressing lifts into and through said mold to form a heel log, suspension rods supported by and depending from the mold, elongated vertical guide bars loosely supported by said rods below the mold and adapted to guide a heel log emerging therefrom, and means for yieldingly pressing the guide bars against the heel log.

In testimony whereof I have affixed my signature, in presence of two witnesses.

WENDELL P. BOSWORTH.
